FOREIGN PATENT DOCUMENTS

JP 749480 11/1998

Primary Examiner — Jennifer O King(74) *Attorney, Agent, or Firm* — K&L Gates LLP; Louis Cullman; Georgia N. Keffalinos(57) **CLAIM**

The ornamental design for an electrical connector cover, as shown and described.

DESCRIPTION

FIG. 1 is a front view of an electrical connector cover of our design.

FIG. 2 is a rear view of the electrical connector cover of FIG. 1.

FIG. 3 is a first side view of the electrical connector cover of FIG. 1.

FIG. 4 is a second side view of the electrical connector cover of FIG. 1.

FIG. 5 is a top view of the electrical connector cover of FIG. 1.

FIG. 6 is a bottom view of the electrical connector cover of FIG. 1.

FIG. 7 is a front perspective view of the electrical connector cover of FIG. 1; and,

FIG. 8 is a rear perspective view of the electrical connector cover of FIG. 1.

The nine recessed surfaces of the front face which are adjacent to the outer edges of the device are of the same plane.

1 Claim, 8 Drawing Sheets(56)
